DESIGN FOR A FLOWERPOT COVER

Oscar Lion, New York, N. Y.

Application April 29, 1942, Serial No. 106,746

Term of patent 7 years

To all whom it may concern:

Be it known that I, Oscar Lion, a citizen of the United States of America, residing in New York city, county of New York, and State of New York, have invented a new, original, and ornamental Design for a Flowerpot Cover, of which the following is a specification, reference being had to the accompanying drawing, forming part thereof, wherein:

I claim:

The ornamental design for a flowerpot cover, substantially as shown.

OSCAR LION.
